UNITED STATES PATENT OFFICE.

WILLIAM R. HAGER, OF CHICAGO, ILLINOIS, ASSIGNOR TO TROY LAUNDRY MACHINERY CO., LTD., OF CHICAGO, ILLINOIS, A CORPORATION OF NEW YORK.

DRYROOM TUMBLER.

Application filed January 24, 1920. Serial No. 353,730.

To all whom it may concern:

Be it known that I, WILLIAM R. HAGER, a citizen of the United States, residing at Chicago, in the county of Cook and State of Illinois, have invented certain new and useful Improvements in Dryroom Tumblers, of which the following is a specification.

This invention relates to dryroom tumblers.

10 As is well understood in the art, it is common practice to provide driving mechanism for dryroom tumblers whereby the rotatable member in which clothes are dried is rotated a given number of revolutions in one direction and then reversed to rotate a given number of revolutions in the opposite direction. Under such conditions the air driven into the rotary member for drying the clothes therein, is not at all times directed upon the clothes for quickly and efficiently drying same.

Accordingly, one object of my invention is to direct the flow of air to the rotatable member in which clothes are dried in a manner such that the clothes at all times are under the drying influence of the drying medium.

Another object is to provide a dryroom tumbler with means whereby the clothes therein may be dried more quickly and in a more approved and efficient manner.

These and other objects are accomplished by means of the arrangement disclosed on the accompanying sheets of drawings, in which—

Figure 1 is an end elevation, parts being in section, of a dryroom tumbler embodying my invention; and,

Figure 2 is a top plan view of the same, parts being broken away and showing operative parts of my invention.

The various novel features of the invention will be apparent from the following description and drawings and will be particularly pointed out in the appended claims.

Referring to the figures of the drawings, it will be noted that I have shown a dryroom tumbler having the usual outer casing 10, including a pivotally mounted door 11, by means of which clothes are placed into and withdrawn from the rotary member 12 of the dryroom tumbler, it being un-

derstood that the rotary member is mounted upon a shaft 13 suitably supported in bearings of the housing. One compartment 14 within the housing 10 is provided with the usual heating coils 15 past which air is blown by a fan 16, the casing 17 of which is in communication with the heating compartment 14. The air, after being heated in the compartment 14, passes outwardly therefrom through a passageway 18 within the casing. Heretofore the hot air has passed through this conduit directly to and through an opening 19 in the upper part of the casing 10 directly over the rotary clothes containing member 12 so that a blast of hot air is directed into the rotary member 12 for drying the clothes placed therein.

As is well understood, it is common practice to drive the rotary member 12 a given number of revolutions in one direction and then reverse the rotary member for driving the same a given number of revolutions in the opposite direction. With this in mind, it will be apparent that if the rotary clothes containing member 12 is rotating in a counterclockwise direction, as viewed in Figure 1, the hot air passing through opening 19 will be directed against the clothes, which will pile up on the right-hand side of the rotary member, thereby playing directly upon the clothes therein for efficiently drying the same at such time. On the other hand, however, when the rotary member 12 is reversed and rotates in a clockwise direction, as viewed in Figure 1, it will be appreciated that the clothes will pile up on the left-hand side of the rotary member and that the hot air which passes through opening 19 will not come into direct engagement for efficiently drying the clothes, but, on the other hand, will be by-passed through the rotary member 12 on the right-hand side of the same. Therefore, the drying medium will be efficient for drying clothes only when the rotary member is rotated in one direction.

To overcome this undesirable feature, I have provided means whereby a drying medium may be supplied directly against the clothes in the rotary clothes-containing member 12 regardless of its direction of movement. To accomplish this result, I have provided a second opening 20 in the inner wall 21 of the passage-

way 18. Thereby the drying medium may be directly supplied to the clothes in the rotary member when the latter is rotated in a clockwise direction. In order to have 5 a strong blast of air and to have the machine operate efficiently from this point of view, I have provided a valve or damper 22 in the passageway 18 which may be moved into one position for closing the 10 opening 20 and permitting air to flow through the passageway 18 and through the opening 19 for drying the clothes when the rotary member 12 is rotating in a counterclockwise direction. This damper 22 also 15 may be moved into a position to close the passageway 18 above the opening 20 to prevent the passage of air to the opening 19 and causing the flow of the drying medium through the opening 20, whereby the drying 20 medium will be supplied directly against the clothes in the rotary member 12 when the latter is rotating in a clockwise direction.

It will be appreciated, of course, that the 25 operation of this damper 22 to be effective must be automatic. Accordingly, I have provided means whereby the damper 22 will be moved from one position to the other upon a change in rotation of the rotary 30 member 12. This means includes a wheel 23 mounted upon the shaft 13, said wheel having a surface which cooperates with a shoe 24 pivotally connected to an arm 25, one end of which at 26 is pivotally connected 35 to one end of a link 27, the other end of which is pivotally connected at 28 to an arm 29 fixed to the pivotal rod 30 of the damper 22. An intermediate portion of the arm 25 is provided with an elongated slot 31 for 40 the reception of the reduced end 32 of a stud 33 secured to one end of the casing 10 in any suitable manner.

Secured to the stud 32 is one end of a 45 spring 34, the other end of which is secured to an ear 35 formed on the arm 25 near the upper end thereof, the action of the spring being such as to yieldably hold the arm 25 in its downward limiting position in which the stud 32 occupies the upper extreme end 50 of the slot 31.

As shown in full lines in Figure 1 of the drawings, it will be noted that the shoe 24 is at the right-hand side of the wheel 23 and that the damper 22 is in a position to prevent 55 the flow of air to the opening 19, but permitting the flow of air through opening 20 for causing a flow of air directly upon the clothes in the rotary member 12 with the latter rotating in a clockwise direction.

60 With the parts in these positions, it will be understood that if the rotary member is now reversed in its rotation so that it rotates in a counterclockwise direction, as viewed in Figure 1, the shoe 24 engaging the peripheral surface of the wheel 23 will be caused

70 to ride thereon in a counterclockwise direction, thereby overcoming the action of the spring 34, the arm 25 first raising so that the stud 32 occupies the lower extremity of slot 31 and the arm at the same time pivoting about the stud 32, causing the damper 22 to move into a position closing the opening 20 to permit the flow of hot air through the conduit 18 and opening 19 against the clothes which are now piled up on the right-hand side of the rotary member 12 as a result of the counterclockwise rotation of the latter. Likewise, the damper 22 will be moved into its full line position when the rotary member 12, and therefore the wheel 23, is reversed and moved in a clockwise direction.

75 In this way the clothes in the rotary member are dried quickly and satisfactorily with the air at all times directed against the clothes in a manner to produce the best results, the action throughout being automatic.

80 It is my intention to cover all modifications of the invention falling within the spirit and scope of the following claims.

85 I claim:

1. In a dryroom tumbler, the combination of a reversibly rotatable member in which clothes are dried, and means whereby a drying medium may be directed against the clothes at one side or the other of said member according to the direction of rotation of the same.

90 2. In a dryroom tumbler, the combination of a reversibly moving container for clothes to be dried, means directing a drying medium to said container, and means automatically changing the direction of said drying medium with changes in the direction of movement of the container.

95 3. In a dryroom tumbler, the combination of a cylindrical container for clothes to be dried rotatable alternately in opposite directions, air delivery openings spaced apart in the direction of the circumference of said container, an air flue for delivering air to said openings, and means directing the flow of air through said openings alternately as the container reverses its rotation.

100 4. In a dryroom tumbler, the combination of a reversibly rotatable member in which clothes are dried, a passageway having two openings through which a drying medium may be supplied to said member, and a damper in said passageway for controlling the flow of drying medium to one or the other of said openings.

105 5. In a dryroom tumbler, the combination of a reversibly rotatable member in which clothes are dried, a passageway having two openings through which a drying medium may be supplied to said member, a damper in said passageway for controlling the flow of drying medium to one or the other of said openings, and means respon-

sive to the direction of rotation of said member for moving said damper to one position or another.

6. In a dryroom tumbler, a cylindrical container for clothes to be dried rotating alternately in opposite directions, means for delivering drying medium in different directions to said container, a damper for con-

trolling the direction of such delivery, a lever connected with said damper for imparting movement thereto, and a wheel revolving with said container and actuating said lever in opposite directions. 10

Signed at Chicago, Illinois, this 20th day of January, 1920.

WILLIAM R. HAGER.
